UNITED STATES PATENT OFFICE.

EDWARD E. BARRETT, OF LA GRANGE, ILLINOIS.

AUTOMATIC HOISTING DEVICE.

No. 901,943.

Specification of Letters Patent.

Patented Oct. 27, 1908.

Application filed July 3, 1908. Serial No. 444,779.

To all whom it may concern:

Be it known that I, EDWARD E. BARRETT, a citizen of the United States, residing at La Grange, in the county of Cook and State of Illinois, have invented a certain new and useful Improvement in Automatic Hoisting Devices, of which the following is a specification.

My invention relates to automatic hoisting devices.

It is illustrated in the accompanying drawings, wherein

Figure 1 is a vertical section through a shaft containing two hoisting receptacles, the parts shown diagrammatically; Fig. 2 is a detail cross section on the line 2—2 of Fig. 1; Fig. 3 is a detail side elevation of the power device and associated mechanism, with parts broken away. Fig. 4 is a detail 20 of the power operating lever.

Like parts are indicated by the same letter in all the figures.

A, A are the framing parts on which the several devices are mounted, and A¹ A¹ the pit walls and bottom.

B, B are receptacles, in this case buckets, united by a common cable B¹ which passes over pulleys B² B² at the top, guide pulleys B³ B³, and about the drum B⁴ actuated by 30 the driving shaft B⁵. This shaft is driven in any desired manner. I have shown it provided with a crank plate C to which leads the connecting rod C¹ connected with the piston rod C² in the power cylinder C³.

D is a controller, in this case a controller lever, pivotally mounted at D¹ and having at its lower end the arms D², D³. To the arm D² is connected one end of the rod D⁴, the other end of which is pivoted to the link D⁵ 40 which is connected to the throttle valve D⁶. The parts are so related that when the controller lever D is upright in the position shown in full lines the throttle valve is closed and the machine out of operation.

To the arm D³ is attached one end of the rod E, the upper end of which is pivoted to the link E¹ having the arc shaped slot E². The link is connected to the lower rocker arm E³, and the upper rocker arm E⁴ to the 50 rod E⁵ which enters the steam chest E⁶ and is used to move the valves. The eccentrics E⁷ and E⁸ are connected each by its respective rod E⁹ and E¹⁰ to the link E¹ in the usual manner. These several parts constitute the 55 reversing mechanism or reverser.

G is a cable from the eye G¹ which is connected by the link G² to one arm G³ of the elbow crank lever, the other arm of which G⁴, is provided with a roller G⁵ at its free end. The two arms of the elbow crank lever are 66 pivoted to the shaft G⁶ which is mounted in the side of the pit. The roller G⁵ takes under a ledge G⁷ formed upon the sides of the bucket. There are four of such arms to each of the two sides of the bucket. They 65 are normally at rest but are rocked when the rollers G⁵ engage the ledge G⁷. One of these cables is associated with each receptacle or bucket and each cable passes over a pulley G⁸ and is connected with the controller lever 70 D. The controller lever D has preferably associated with it a dash-pot structure J having the pitman J¹ and the link J² which has a long slot J³ through which passes the pin J⁴ on the controller lever.

K is a portion of a bin and L a discharge opening therein from which material, as for example coal, is discharged into the bucket when it reaches the lower end of its excursion. Some automatic device is usually employed but as this is no part of my present invention I do not show the same. Moreover, so far as the hoisting mechanism is concerned it will operate in precisely the same manner whether hand or automatic mechanism is employed for filling the buckets.

It will be understood that these several features can be greatly varied without departing from the spirit of my invention, and I wish it to be understood that my drawings are in fact, largely diagrammatic although sufficient detail is given to fully instruct any one desiring to make use of the invention. Some parts could be omitted and some could have different devices substituted without departing from the spirit of my invention. I have shown buckets but any other suitable receptacle could be employed. I do not show the method of filling or emptying the buckets. It will be understood that there are means for automatically filling each bucket as it reaches the lower end of its excursion, for example, with coal if the device is used as a coal hoist. There are also means at the top for automatically discharging the 105 coal into a bin or car. I have shown two buckets but some portions of my invention may be realized by a single bucket and more than two buckets could be employed.

The use and operation of my invention are 110

as follows: When the buckets are in the position shown in Fig. 1 they are connected by a hoisting cable and the drum around which the cables are wound. One bucket is at the top of its shaft while the other is at the bottom of its shaft. Under these circumstances the controller or controller lever D should be in its upright position or in that position in which the power mechanism is throttled. This is accomplished as follows: The bucket on the right hand side having descended far enough, its projecting ledge engages the rollers on the elbow crank levers and as the bucket further descends these lever arms are forced down, the elbow crank levers rocked on their supporting shafts and the cable G is downwardly pulled and this will bring the lever D to the upright position indicated in the drawings. It will be understood, referring to Fig. 3, that the lever was in the position of the dotted lines, or turned at the top toward the left when this action began. The bucket, the moment it strikes the elbow crank levers, depresses them freely and rapidly and the lever is brought from the position of the dotted lines to the vertical position shown in Fig. 3 very promptly because the pin J⁴ moves freely through the slot J³. This, however, throttles the power. The increasing weight of the material in the bucket tends to lower it further but now it operates against the action of the dash-pot so that its downward motion is impeded. Eventually, however, the continued pull on the cable will throw the lever over toward the left at the top in the position of the second dotted line. This action will reverse the engine by its action on the reverser or reversing mechanism illustrated in Fig. 3. However, the parts are so related that at this moment the top bucket has emptied its load, the lower bucket is full, and the reversed engine applying the power causes the full bucket to rise and the empty one to descend. When they approach the limits of these movements the same action is repeated in an inverse sense and thus I have provided an automatically operating device. If it be associated with automatic bucket loading and emptying devices it will be seen that the apparatus will thus continue to operate without attention from the operator.

I claim:

1. In an automatic hoisting device, the combination of two receptacles with a hoisting cable, the receptacles associated so that one is at one end of its excursion while the other is at the opposite end of its excursion, a power device for operating the cable, a power reverser and a power throttle for the same, a controller connected with the reverser and the throttle, a lost motion device and a dash-pot device connected with such controller, and two controller motors comprising each a movable part in the path of

one of the receptacles and a connection thence to the controller to alternately operate the same in opposite directions.

2. In an automatic hoisting device, the combination of two receptacles with a hoisting cable, the receptacles associated so that one is at one end of its excursion while the other is at the opposite end of its excursion, a power device for operating the cable, a power reverser and a power throttle for the same, a controller connected with the reverser and the throttle, a lost motion device connected with the controller, and two controller motors comprising each a movable part in the path of one of the receptacles and a connection thence to the controller to alternately operate the same in opposite directions.

3. In an automatic hoisting device, the combination of two receptacles with a hoisting cable, the receptacles associated so that one is at one end of its excursion while the other is at the opposite end of its excursion, a power device for operating the cable, a power reverser and a power throttle for the same, a controller connected with the reverser and the throttle, and two controller motors comprising each a movable part in the path of one of the receptacles and a connection thence to the controller to alternately operate the same in opposite directions.

4. In an automatic hoisting device, the combination of a receptacle with a hoisting cable, a power device for operating the cable, a power reverser and a power throttle for the same, a controller connected with the reverser and the throttle, a lost motion device and a dash-pot device connected with such controller, and a controller motor comprising a movable part in the path of the receptacle and a connection thence to the controller.

5. In an automatic hoisting device, the combination of a receptacle with a hoisting cable, a power device for operating the cable, a power reverser and a power throttle for the same, a controller connected with the reverser and the throttle, a lost motion device connected with such controller, and a controller motor comprising a movable part in the path of the receptacle and a connection thence to the controller.

6. In an automatic hoisting device, the combination of a receptacle with a hoisting cable, a power device for operating the cable, a power reverser and a power throttle for the same, a controller connected with the reverser and the throttle, and a controller motor comprising a movable part in the path of one of the receptacles and a connection thence to the controller.

7. In an automatic hoisting device, the combination of two receptacles with a hoisting cable, the receptacles associated so that one is at one end of its excursion while the other is at the opposite end of its excursion, a

power device for operating the cable, a power reverser and a power throttle for the same, a controller lever connected with the reverser and the throttle, a lost motion device and a dash-pot device connected with such controller lever, and two controller motors comprising each a movable part in the path of one of the receptacles and a connection thence to the controller lever to alternately operate the same in opposite directions.

8. In an automatic hoisting device, the combination of two receptacles with a hoisting cable, the receptacles associated so that one is at one end of its excursion while the other is at the opposite end of its excursion, a power device for operating the cable, a power reverser and a power throttle for the same, a controller lever connected with the reverser and the throttle, a lost motion device connected with such controller lever, and two controller motors comprising each a movable

part in the path of one of the receptacles and a connection thence to the controller lever to alternately operate the same in opposite directions.

9. In an automatic hoisting device, the combination of two receptacles with a hoisting cable, the receptacles associated so that one is at one end of its excursion while the other is at the opposite end of its excursion, a power device for operating the cable, a power reverser and a power throttle for the same, a controller lever connected with the reverser and the throttle, and two controller motors comprising each a movable part in the path of one of the receptacles and a connection thence to the controller lever to alternately operate the same in opposite directions.

EDWARD E. BARRETT.
